DISAPPEARING CHAIR

Eugene E. Elder, Los Angeles, Calif., assignor to
Mildred H. England, Hollywood, Calif.

Application June 29, 1939, Serial No. 281,797

10 Claims. (Cl. 155—124)

My invention relates to disappearing chairs for tables, counters, bars, desks, and the like.

An important object of the invention is to provide guide means for directing movement of the chairs to and from a disappeared position.

Still another object relates to providing a track for such chairs which will direct movements of the chairs to and from a disappeared position.

The invention also comprises novel details of construction and novel combinations and arrangements of parts, which will more fully appear in the course of the following description.

In the drawing, like reference characters designate similar parts in the several views.

Figure 1 is a vertical section of an embodiment of my invention.

Figure 2 is a transverse section taken on the line 2—2 of Figure 1, looking in the direction of the arrows.

Figure 3 is a sectional view similar to Figure 1, except that it shows a modified construction.

Figure 4 is a transverse section taken on the line 4—4 of Figure 3.

Figure 5 is a reduced plan view of either embodiment shown in the other figures in the drawing.

Referring more in detail to the drawing, the reference numeral 6 designates a table that is provided with a center pedestal 7. While the table is shown in the drawing as round, it is to be understood that tables of other shapes may also be used. Moreover, the present invention is applicable to desks, counters, bars, and the like.

A base member 8 or 9 may be used to support the pedestal. In the form shown in Figures 1 and 2, the base member 8 terminates in flexible ends 10 and 12. These flexible ends may be slats 13 hinged together with the pintles 14 at the upper surface of the base member, when the slats are aligned in a horizontal plane. The slats 13 may be flexibly connected by any other suitable means.

Chairs 15 and 16 are arranged at opposite sides of the table 6 and arranged to roll under the table. These chairs contain vertical slots 17 and rollers 18 and 19 mounted on axles 23 and 24 on brackets 20 and 21 respectively on braces 11 of the chairs. Cushions 22 may be applied to the chairs.

In the form shown in Figures 3 and 4, the base member 9 terminates in ends 25 and 26, hinged to the base member at 27 and 28 respectively. Chairs 29 and 30 are arranged at opposite sides of the table and arranged to roll under same.

The chairs 29 and 30 have relatively stationary, downwardly and forwardly curved slides 31

and 32. The slides have lower end abutments 33. Lugs 34 on the ends 25, 26 support rods 35, which slide laterally up and down the slides 31, 32.

5 Bearings 36 and 37 support front and rear rollers or wheels 38 and 39 respectively.

It will be noticed that the flexible ends 10, 12, in the form shown in Figures 1 and 2, extend substantially from one side 40 to the other of

10 the chair, so as to reduce to a minimum side play between the chair 16 and its guide. In the form shown in Figures 3 and 4, the hinged ends 25, 26 extend substantially from one wheel 38 to the other and substantially from one side 41 to the

15 other of the chair 30, to guide the in-and-out movements of the chair. The sides 40, 41 act as legs for the chairs.

The termini of the flexible ends 10, 12 carry rods 45, which slide in opposed grooves 46 in the inner faces of the sides 40. The ends of the grooves 46 limit lateral movement of the rods and thereby limit inward and outward movement of the chairs 15 and 16.

20 The use of the present invention is believed clear. The chairs when not in use may be moved to an out-of-the-way position under the table, desk, counter, bar, etc. The guides 10 and 12 in Figures 1 and 2 and the guides 25 and 26 in Figures 3 and 4 direct the movements.

25 When the chairs 29, 30 are in their inward positions, the hinged guide-ends are upright, as shown under the chair 29 in Figure 3. The rod 35 is at the top of the slides in this position.

As the chairs 29, 30 are moved outward from the table, the rod 35 slides laterally down the slides until it is stopped by the abutments 33 at the foot of the slides. At this time, the hinged ends 26 are lying horizontal. Inward movement of the chairs 29, 30 causes the rod 35 to ride up the slides.

30 The chairs 15 and 16 show different positions of the same form of the invention, and chairs 29 and 30 show different positions of another form of the invention.

35 It is to be understood that in the hereunto appended claims the word "table" shall also be taken to include desk, counter, bar and the like.

40 While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire 45 to avail myself of all modifications which may

fall within the scope of the appended claims.

Having thus described my invention, what I claim and desire to secure by Letters Patent is:

1. In combination, a table, a chair having legs supporting the same, and a guide in movable connection with, and in lateral relation to, the table, between the legs of the chair extending toward the table, the said guide extending substantially from side to side of the chair in slideable relation therewith and being vertically shiftable within the chair as the latter is moved to and from the table in the path defined by the guide.

2. In combination, a table, a chair movable to and from the table, a guide in movable connection with, and in lateral relation to, the table, and slideable in connection with the chair for directing movement of the chair in a path to and from the table, the guide being flexible in a vertical direction, and means effecting the upward flexing of said guide, within the chair, when the chair is moved toward the table.

3. In combination, a table, a chair movable to and from the table, a guide for the chair extending laterally from the table outward to define a path of movement of the chair, roller means on the chair disposed to roll on the guide, the guide being flexible, and means to direct the flexible guide upward within the chair when the chair is moved toward the table.

4. In combination, a table, a chair movable to and from the table, a guide for the chair extending laterally from the table outward to define a path of movement of the chair, and comprising a series of slats flexibly connected together, and means to flex said guide and direct the slats into the chair, when the chair is moved toward the table.

5. A chair movable on a supporting surface and having a slot, and a laterally extending guide on said supporting surface for guiding the chair in its movements, comprising a series of slats flexibly connected together for vertical yielding movement within the slot of the chair.

6. A chair movable on a supporting surface, a

laterally extending movably connected guide on said supporting surface extending beneath the chair, said guide being vertically shiftable with respect to the supporting surface and within the chair, and means within the chair to cause the said guide to shift vertically within the chair as the chair is moved lengthwise of the guide.

7. A chair, rollers for said chair at the sides thereof for movement on a supporting surface, a lateral guide movably connected to said supporting surface and extending within the chair from one side roller to the other, said guide being flexible in a vertical direction, and slide means within the chair in connection with said guide for flexing the latter vertically as the chair is moved lengthwise of the guide.

8. In combination, a table, a chair movable to and from the table, sides on the chair, curved slides extending upwardly on the inner sides of the chair, a guide extending laterally from the table and within the chair substantially from side to side of the chair, said guide having a hinged connection with the support for the table on which it is swingable vertically in the chair, and a rod connected with the hinged guide and disposed to ride up the slides when the chair is moved toward the table.

9. In combination, a table, a chair movable to and from the table, a movable guide for the chair extending laterally from the table outward to define a path of movement of the chair, and means to shift the guide vertically and progressively within the chair as the chair is moved toward the table.

10. In combination: a table to be supported by a floor, a chair movable with respect to the table to and from a position substantially under the table, and a guide movably connected to the table support arranged to rest on the floor and to extend outward laterally with regard to the table, the chair having a sliding connection with the guide to direct said movements of the chair, and means to shift the guide vertically within the chair during movements of the chair in guided relation toward and away from the table.

EUGENE E. ELDER.
